UNITED STATES PATENT OFFICE.

HIRAM C. J. DEEKS, OF SEA CLIFF, NEW YORK, AND MAURICE DEEKS, OF ROCHELLE PARK, NEW JERSEY, ASSIGNORS TO JOSEPH DEEKS, OF SEA CLIFF, NEW YORK.

METHOD OF AND APPARATUS FOR FORMING CONCRETE STRUCTURES.

Application filed September 18, 1920. Serial No. 411,238.

To all whom it may concern:

Be it known that we, HIRAM C. J. DEEKS, a citizen of the United States, residing in Sea Cliff, county of Nassau, and State of New York, and MAURICE DEEKS, a subject of the Kingdom of Great Britain, residing in Rochelle Park, county of Bergen, and State of New Jersey, have invented an Improvement in Methods of and Apparatus for Forming Concrete Structures, of which the following is a specification.

The present invention relates to an improvement in method of and apparatus for forming concrete structures, the general purpose being to provide a method which can be practiced by means of relatively cheap and easily obtainable devices and which will be capable of rapid and effective application.

One form of apparatus by means of which our improved method may be practiced is illustrated in the drawings accompanying the present specification and in which

Figure 1 is a general plan view,

Figure 2, an elevation with a portion in transverse vertical section,

Figure 3, a view in perspective of concrete retaining side members,

Figure 4, a view in perspective of the yoke member,

Figure 5, a view in perspective of the core spacer,

Figure 6, a view in perspective of a portion auxiliary to the yoke,

Figure 7, an enlarged detail view partly in transverse vertical section of a portion of our concrete structure with the apparatus in position for forming the next increment thereof,

Figure 8, a view in detail and partly in horizontal section showing method of joining side members to form corners, and

Figure 9, is a perspective of a tie rod depression former.

Referring to the drawings, more particularly Figure 2, a plurality of rods 1 are positioned in channels 2 formed in a previously constructed increment of the wall, in this case shown as a double wall with air space between the opposed sections thereof. The rod 1 is secured to and supports a yoke having uprights 3 and 4 and a cross head 5. As indicated more clearly in Figure 4, the upright 3 is provided with a forked portion

at its lower end within which is mounted a nut 6. The lower end of the upright 4 is provided with a rod receiving channel 7 in alignment with the nut 6. Thus to assemble the yoke upon the rod 1, the latter will be passed through the channel 7 and will engage the nut 6. The rod 1 is preferably provided at one end with a head 8, and a collar 9 is preferably interposed between said head and the adjacent face of the upright 4 to permit easy access to the head of the rod.

In assembling the forms for pouring a new increment of concrete, the rods 1 are positioned transversely of the base and supported by spaced surfaces which are uniformly level with respect to each other. The exterior concrete retaining means may consist of a plurality of vertical retaining members made up of suitable lengths of ordinary board 10, preferably assembled to form a framework consisting of uprights 11 and longitudinal members 12. Where the side wall retaining member is intended to abut against another similar member to retain the interior side adjacent to a corner, an additional upright member 13 may be provided and will be assembled as indicated more clearly in Figures 1 and 8. With the exterior side wall retaining members in position, supported by the rod 1, the upright members of the yoke may be inserted between the boards 10 and the side frame pieces 12 and positioned so that the rod 1 will engage the nut 6 and the channel 7 as hereinabove described. By tightening up on the head 8, the boards 10 will be pressed tightly against the outside surfaces of that portion of the structure previously formed. Referring now to Figure 7, the cross head 5 of the yoke is provided with channel forming members 14 depending from said cross head to a position below the level of the upper edges of the boards 10. These channel forming members 14 are preferably tapered, as indicated in Figure 4, and may be conveniently constructed as there indicated by means of blocks of wood 15 to which are secured strips of metal of suitable shape. Where the concrete construction is solid, the members 14 will be connected to form in effect a single continuous channel forming or shaping member, this result being accomplished by suitable means here shown as a removable metallic member

16 adapted to overlap portions of each of the members 14 and to be secured thereto by any suitable means.

Where the concrete construction is hollow, 5 the apparatus will include a suitable core, more clearly shown in Figure 7. A core for this purpose may include vertical concrete retaining members 17 adapted to rest on tie pieces 18 supported in channels 30 formed 10 in the previously completed increments of concrete structure. The retaining members 17 are held in spaced relation by a spacer, one suitable form of which is illustrated in Figure 5 and includes tapered uprights 19 15 with suitable interposed cross pieces, and a cover 20 having depending flanges 21, said cover being preferably tapered from one end to the other as more clearly indicated in Figure 1, thus permitting one cover to overlap an adjacent cover. A metallic rod may 20 be secured to the spacing member in such a manner as to form a handle or bail 22 by means of which the spacer is conveniently moved into and out of operative position. 25 In assembling, after the retaining members 17 have been placed in position on the ties 18, the tapered uprights of the spacer are moved down between said retaining members until the cover 20 rests upon the upper 30 edges thereof with the flanges 21 overlapping the upper portions of said retaining members. The assembled core is retained in upright position and properly centered by means of the depending channel forming 35 members 14 of the yoke. While the core is in proper position and after the increment of concrete has been poured, a channel forming block 23 (Figures 2 and 9) having a central opening 24 adapted to fit over a portion 40 of the core and flat bearing portions 25 to engage the upper surfaces of the exterior concrete retaining member 10, is applied at intervals by being pressed or otherwise forced into the upper surface of the concrete to form spaced tie receiving depressions or channels 30.

In practicing our method which may conveniently be carried out by means of the apparatus hereinabove described, we form a 50 base having spaced transverse uniformly level portions, these portions being adapted to receive and support the rods or their equivalent hereinabove referred to. The forming of the base or foundation may be 55 accomplished in any well known manner, the main object being to provide a substantial foundation with spaced transverse portions all on the same level. It is contemplated that, the level once having been established, succeeding increments of structure 60 will reproduce a similar leveling automatically. With the base established as indicated, our next step is to pour the next increment of concrete and to form in said increment spaced transverse channels below

the normal upper surface of said increment and in vertical alignment with and uniformly distant above the level portions of the base or foundation. The forming of the transverse channels may be and preferably 70 is accomplished during the pouring of the new increment of concrete, this result being accomplished by means of the channel forming member hereinabove described in connection with the yoke. Where all of the 75 yokes are of uniform dimensions and proportions, the distance between the bottoms of a given set of transverse channels and the bottoms of the channel forming members when assembled to form the next succeeding 80 set of transverse channels, will remain constant thereby automatically leveling the structure.

In practicing our method and operating the apparatus described, the foundation or 85 base having been established, we first position the rods 1. The exterior concrete retaining members are then placed in operative position supported by said rods. If the wall is of hollow construction, the ties 18 90 are also placed in position in the channels 30 and the core is supported by means of said ties. We then apply the yoke which is secured to the rod 1 in the manner hereinabove described and which not only establishes the position of the exterior retaining members but also effectively centers or positions the core. The parts of the apparatus are now in position for pouring the concrete. One advantage flowing from the present apparatus and method is that no special care need be exercised in pouring except to be sure that the depth of concrete poured is sufficient to engage the channel forming members. The normal level of each pouring 100 may otherwise vary without injury to the ultimate structure at any convenient time after the pouring or applying of the concrete and while it is still plastic, the tie receiving channels 30 may be formed at 105 suitable intervals along the wall by pressing or otherwise forcing the wedge shaped portions of block 23, or the like in the plastic mass to such an extent that the bottoms of the channels will lie in the same horizontal 110 plane. The channels 30 will preferably not extend entirely across the adjacent walls, but will be sufficiently long in a transverse direction to accommodate the ties 18. Accordingly, each of the channels 18 will be 115 closed at one end and will open into the air space between the walls at the other end. After the mixture of concrete has sufficiently set, the forms may be removed and the rods 1 may be withdrawn from their positions 120 and inserted in a similar position for re-use.

In practicing the method and making use of the apparatus above described, we have effected material savings over well known methods of concrete construction. In the 130

first place, we utilize materials which are readily obtained and which are for the most part of standard size, such for example as the boards forming the exterior concrete 5 retaining members and the lumber utilized in the yoke and spacer. The rods are of ordinary commercial size and design and the ties 18 are those commonly used for similar purposes in the concrete art. The 10 channel forming members 14 and the cover plates 20 are preferably of sheet metal and, being respectively of uniform size and dimension, may be made in quantities at a relatively low price. The assembling of 15 the apparatus is very simple and requires a minimum of skilled labor. Another advantage arising out of the use of our apparatus is that, in the actual pouring of the concrete, the work may be done by unskilled labor inasmuch as the levels are established once and for all when the base 20 or foundation is established.

Other advantages in connection with the use of our method and apparatus will be 25 apparent but we refer particularly to the speed with which concrete construction may be effected. This is partly due to the lightness and simplicity of the apparatus and partly due to the fact that a relatively large 30 increment of concrete can be poured at a single setting of the forms. In other words, where some processes permit the pouring of only eight to ten inches of concrete, we can successfully pour sixteen inches of concrete 35 with a single setting of the forms.

We claim as our invention:

1. Apparatus for forming concrete structures comprising a plurality of transverse rods supported at a uniform level, an upright yoke 40 detachably secured to each of said rods, spaced concrete retaining members maintained in operative position by said rods and said yokes, and a transverse channel forming member depending from each of said yokes to a position below the level of the upper edges of the retaining members.

2. In apparatus for forming hollow concrete structures the combination of a core 50 having overlapping upright retaining members, a tapered spacing member between said retaining members, and a core cover consisting of a plurality of longitudinally tapered members having depending flanges in over-

lapping arrangement and adapted to engage 55 the upper edges of the upright retaining members, and means for supporting said core in operative position.

3. In apparatus for forming concrete structures the combination of spaced vertical concrete retaining members, means for supporting said members, and means for positioning said members including a yoke having a cross piece overlying said spaced members, spaced channel forming members 65 depending from said cross piece, and removable means for connecting said spaced channel forming members to form a single continuous channel forming member.

4. In apparatus for forming concrete 70 structures, the combination of a form supporting rod and a yoke consisting of spaced uprights and a cross member, the free end of one of said uprights having a rod receiving recess open at one side and the free end 75 of the other upright having a rod receiving nut in alignment with the rod receiving recess aforesaid.

5. A core for use with apparatus for forming hollow concrete structures, comprising concrete retaining side walls and positioning means therefor including a tapered spacing member between said walls and core space covering means consisting 80 of a covering member secured to said spacer 85 and overlying the upper edges of both retaining walls thereof.

6. A core for use with apparatus for forming hollow concrete structures comprising concrete retaining side walls and positioning means therefor including a tapered spacing member between said walls and core space covering means secured to said spacer. 90

7. A core for use with apparatus for forming hollow concrete structures comprising concrete retaining side walls and positioning means therefor including a tapered spacing member between said walls and core space covering means consisting of a plurality of covering members tapered longitudinally and having their ends overlapping when in operative position. 95 100

In testimony whereof, we have signed our names to this specification this 9th day of September, 1920.

HIRAM C. J. DEEKS.
MAURICE DEEKS.
